(No Model.)

J. E. GROSJEAN.

FUNERAL ADVERTISING DEVICE OR ANNUNCIATOR.

No. 351,862.

Patented Nov. 2, 1886.

UNITED STATES PATENT OFFICE.

JAMES E. GROSJEAN, OF FREDERICKSBURG, OHIO.

FUNERAL-ADVERTISING DEVICE OR ANNUNCIATOR.

SPECIFICATION forming part of Letters Patent No. 351,862, dated November 2, 1886.

Application filed June 12, 1886. Serial No. 204,975. (No model.)

To all whom it may concern:

Be it known that I, JAMES E. GROSJEAN, a citizen of the United States, residing at Fredericksburg, in the county of Wayne and State of Ohio, have invented certain new and useful Improvements in Funeral-Advertising Devices or Annunciators, of which the following is a specification, reference being had therein to the accompanying drawings.

10 The object of my invention is to provide a simple, neat, and convenient device suitable to be hung in a public place, as the vestibule of a church or elsewhere, for announcing a funeral. To this end my device consists of a plate or tablet adapted to receive several lines of movable letters or words to make up the desired announcement. The tablet is inclosed by a suitable ornamental frame, and the letters or words are preferably protected by a glass.

15 20 To the top of the frame is attached a suspending cord or ribbon, and to the bottom thereof is secured a rack of convenient form to receive the crape by which the device is draped.

In the drawings, Figure 1 represents my funeral-advertising device in full with the crape attached, and Fig. 2 is a section of the same with the crape removed.

A denotes a plate or tablet provided with grooves or ways with overhanging divisions *a*, 30 for the reception of movable letters or words *b*, which make up any desired announcement to give notice of the day, time of day, and place where the funeral of a deceased person is to be held. For this purpose there should 35 be room for several lines or rows of words or letters, four being shown in the drawings. The movable letters or words may be on cardboard or metallic plates or thin blocks of wood and fit loosely in the grooves of the tablet, being slid into the grooves from the ends thereof.

The tablet A is removably attached, as by screws *d*, to a suitable ornamental frame, B, and the latter is provided at its top with a suspending ribbon or cord, *e*, and at its bottom with a rack or wire to which the crape D, by which the device is draped, is attached. This rack consists, in the form of my invention herein shown, of a horizontal wire, C, 45 pointed at one end, and having a bend, *c*, connecting it with a vertical portion, *c'*, attached

to the frame, said bend giving the said wire C sufficient elasticity to enable its pointed end to be readily inserted into and removed from a hook, *c'*, on the lower end of a short wire, *c*, attached to the frame B, the form of the bend *c* being such as to cause the wire C normally to spring downward, so as to be retained in said hook. Thus the pointed end of said wire may be lifted out of the said hook 6c when the crape is to be placed thereon, as in Fig. 1, and when again replaced in the hook there will be no danger of accidental displacement. I prefer to cover the words or letters of the tablet with a glass, E, between said letters and the front of the frame, as shown in Fig. 2.

To change the announcement in the tablet, the latter is removed from the frame by taking out the screws *d*. The words or letters *b* 70 can then be slid out of their grooves and other words or letters inserted to make up any desired announcement. The crape with which the device is draped can, if desired, be used for drapery at the house of the deceased person, either before or after being used to drape 75 the annunciator or funeral advertising device.

Having thus described my invention, I claim and desire to secure by Letters Patent—

1. A funeral-advertising device or annunciator consisting of a tablet provided with words or letters constituting the announcement, combined with a frame in which the said tablet is removably secured, said frame having at its top a suspending device, as a 85 ribbon or cord, and at its lower part a crape-attaching rack.

2. The combination, with the grooved tablet A and the movable words or letters adapted to be slid into the grooves thereof, of the frame B, in which the said tablet is removably secured, the glass E, and the crape-attaching rack attached to the lower part of the said frame, and consisting of the bent and pointed wire C *c* and the hooked wire *c'* *c'*, substantially as set forth.

In testimony whereof I affix my signature in presence of two witnesses.

JAMES E. GROSJEAN.

Witnesses:

A. L. OBER,
W. S. PEPPARD.
